DISPLAY RACK FOR RESILIENT FLOORING SAMPLES OR THE LIKE

Gerard M. Schouten, Lititz, Pa., assignor to Armstrong Cork Company, Lancaster, Pa.

Filed May 15, 1975, Ser. No. 577,640

Term of patent 14 years

Int. Cl. D6—04; D20—02
U.S. Cl. D6—188

The sole figure is a perspective view of a display rack for resilient flooring samples or the like showing my new design.

The rear and side which are not shown are flat and unornamented.

I claim:

The ornamental design for a display rack for resilient flooring samples or the like, substantially as shown.
